UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A NECK-SCARF.

SPECIFICATION forming part of Design No. 11,782, dated May 18, 1880.

Application filed January 28, 1880. Term of patent 7 years.

To all whom it may concern:

Be it known that I, THOMAS J. FLAGG, a citizen of the United States, residing at New York, in the county and State of New York, have invented and produced a new and original Design for Made-Up Scarfs, of which the following is a specification, reference being had to the accompanying drawings, forming part thereof.

5 My design relates to a double-headed or reversible scarf formed with crossed aprons, whose opposite ends are so finished and connected by an intermediate piece as that either end of the complete scarf may be exposed and worn as the head of the scarf.

10 The leading feature of my design consists in an outline for the complete scarf, presenting substantially the general contour of a heart shape at one end, and of two opposed right angles whose upper lines are joined by a curve-line at the other.

15 In the accompanying drawing, A A' are the aprons of the scarf. Each apron is bounded by an extended right line, *a*, forming one edge, 20 a straight line, *b*, at right angles thereto, forming one end, and by a straight line, *c*, which, diverging slightly from parallelism with the first line, *a*, merges about midway of the apron, at *w*, in the line of an elliptical curve, *d*, which, 25 in turn, terminates in a semicircle, *e*, constituting the other end of the apron. The aprons are crossed, with their rounded ends *ee* placed in the same direction, to form, in combination with an interposed neck-piece, B, one end of the 30 scarf, their opposite angular ends constituting, in combination with the opposite neck-piece, B', its opposite end. The upper edges, *ff'*, of each neck-piece are slightly curved inwardly in a line which, at the rounded end of the scarf,

merges into and forms a graceful reversed continuation of the curved lines *ee* of the adjacent ends of the aprons. 40

D is the neck-band, which forms no part of the design.

45 The exterior outline of this design for a double scarf is that of a trapezoid at one end connected with a heart at the other, the trapezoidal end being connected with the heart-shaped end by two straight lines, *k k*, intersecting at right angles the ends *bb* of the 50 trapezoid, to form a hexagon, whose lower side, if projected, (see dotted lines,) would overlap the base of the heart. The outer lines of the heart terminate at their intersection with the inwardly-converging lines *kk* of the hexagon. 55 The upper outer side of the trapezoid is slightly curved inward, and forms the edge *f'* of the neck-piece B'.

I claim as my invention—

60 The design for a double-headed or reversible scarf herein shown and described, the same consisting of two aprons, A A', centrally crossed, each formed with one squared end, *b*, one straight side, *a*, at right angles to said end, a second straight side, *c*, diverging from the 65 squared end *b* at a slightly-obtuse angle, and with an opposite semicircular end, *e*, merging with an elliptical curve into the diverging line *c* about midway of the length of the apron, and in which the aprons are crossed, with their 70 corresponding ends placed in the same direction and connected by inwardly-curved lines *ff'*, to present a trapezoidal outline at one end of the scarf and a heart shape at the other.

THOS. J. FLAGG.
